CLAIM

The ornamental design for a 1×4 distribution point unit with surface ornamentation, as shown and described.

DESCRIPTION

FIG. 1 is a front perspective view of a 1×4 distribution point unit with surface ornamentation, showing our new design;

FIG. 2 is a bottom view thereof;

FIG. 3 is a top view thereof;

FIG. 4 is a right view thereof;

FIG. 5 is a left view thereof;

FIG. 6 is a front view thereof; and,

FIG. 7 is a rear view thereof.

The broken lines immediately adjacent to the claim represent the bounds of the claimed design, while all other broken lines are directed to environment; the broken lines form no part of the claimed design.
